METHOD OF EMBALMING

Harry S. Day, Youngstown, Ohio

Application April 10, 1940, Serial No. 328,901

3 Claims. (Cl. 27—22)

This invention relates to a method of embalming.

The principal object of this invention is the provision of a method of purging a body of blood and effecting an efficient capillary wash and the subsequent adequate embalming with suitable embalming fluid.

A further object of the invention is the provision of a method of obtaining a better cosmetic effect on a body through the more adequate purging of the blood from the capillaries and the replacement thereof with a suitable embalming fluid.

A still further object of the invention is the provision of a method of embalming wherein the tissues of the body may be built up evenly and perfectly to overcome the wasting effects of illness through the application of a partial vacuum to the body and the simultaneous influx of suitable embalming fluid.

A still further object of the invention is the provision of an economical method of embalming particularly as concerns the time and effort customarily spent in manual massage of the body in effecting an efficient capillary wash.

With the foregoing and other objects in view which will appear as the description proceeds the invention resides in the methods and mode of procedure and in the details thereof herein-after described and claimed, it being understood that changes in the precise methods and procedure herein disclosed can be made within the scope of the appended claims without departing from the spirit of the invention.

Apparatus used in applying the method of embalming hereinafter described and claimed is illustrated in the accompanying drawing wherein the figure is a perspective view of a suitable pressurable operating chamber showing various details of construction and the several cooperative parts attached thereto.

By referring to the drawing it will be seen that a suitable operating chamber of a size sufficient to receive a body has been shown. The operating chamber, as indicated by the numeral 10 in the drawing, is shown positioned on legs 11 for the suitable elevation of the same, placing it at a convenient height for the operator. A broad peripheral flange 12 is formed about the upper edge of the operating chamber 10 which is itself box like in shape. This broad peripheral flange 12 carries a suitable rubber gasket 13 adapted to form an air tight joint when a loosely hinged lid portion 14 is closed thereupon and a plurality of clamps 15 moved into engagement with the upper

surface of the lid 14 and clamped in position so as to firmly affix the lid 14 to the operating chamber 10 in an air tight manner. By referring to the lid 14 it will be seen that a plurality of electric lights 9 have been positioned on the interior surface thereof so that a body positioned within the operating chamber may be suitably illuminated thereby. In order that the operator may inspect the body from time to time, a pair of suitable pressure withstanding windows 16 are positioned within the lid 14. The lid 14 is loosely affixed to the operating chamber 10 by means of slip hinges 17 so that they will not interfere with the tightening action of the clamps 15 when the lid is in place.

By referring to the structure shown at the right end of the operating chamber 10 it will be seen that a pair of non-collapsible tubes 18 terminate outside of the operating chamber 10 and lead into the interior thereof. The pair of non-collapsible tubes 18 are provided to insure a communication channel of adequate capacity. A housing 19 encloses an electric motor and a suitable air pump and carries on a conveniently shaped surface 20 thereof a pair of gauges 21 which are adapted to register vacuum or air pressure within the operating chamber. A lever 22 controls the action of the air pump so that it either exhausts the air from the operating chamber and creates a partial vacuum therein or builds up the pressure in the operating chamber in any desired degree. It is obvious that tanks may be incorporated wherein reserve air pressure or vacuum may be built up so that the operator need not wait for the air pump to establish the same. Controls are also provided for varying the action of the air pump and releasing the air pressure as desired together with controls for an exhaust fan which may be connected to the operating chamber 10 if desirable. Having thus shown and described suitable apparatus for accomplishing an embalming process under the methods herein claimed, the following description of the embalming method is given.

It is well known that embalming comprises several different although allied operations one of the first of which is the operation wherein the blood in the various veins and capillaries in the body is purged from the body. It is essential that all the blood be purged from the body in that any particles remaining may adversely affect the preservation of the body by interfering with the action of the embalming fluid. In order to accomplish this with a minimum of effort and

without the necessity of manually massaging the body tissues, which incidentally often results in the rupture of the capillaries near the surface of the skin and causes a discoloration which is objectionable, the body may be conveniently placed in the operating chamber 10 and suitable incisions made to enable the non-collapsible tubes 18 to be placed in operative locations in the deeper vessels of the body such as are found in the sacro-iliac axis or thereabout. The lid 14 of the operating chamber is then closed and the mechanism attached thereto operated until a suitable air pressure has been built up within the operating chamber. The air pressure will effectively collapse the tissues and capillaries and 15 the veins and arteries and drive the blood therefrom into the deeper vessels of the body from whence it drains from the body and operating chamber through the tubes 18.

The second desirable operation in embalming is the operation of washing the capillaries so as to dissolve particles of blood remaining therein so that these particles may be effectively removed from the body. This is accomplished by reversing the action of the air pump associated with the 25 operating chamber 10 and establish a partial vacuum within the said chamber. At the same time the operator supplies the tubes 18 with a suitable capillary washing fluid under slight pressure if necessary. Due to the partial vacuum existing about the body the natural tendency of the capillary washing fluid is to penetrate the veins and arteries and capillaries of the body from which it may be readily purged by again 30 reversing the action of the air pump and establishing pressure within the air chamber 10 which will cause the capillary washing fluid to drain from the body and the chamber through the tubes 18. This may be repeated until the operator is satisfied through his visual inspection through the window 16 and through his inspection of the 35 capillary wash that the blood particles have been completely dissolved and removed from the body. When this has been accomplished all 40 of the capillary washing fluid is of course purged from the body by the air pressure means and the operation of embalming the body may then take place. The operation of embalming the body comprises the supplying of the tubes 18 with a suitable embalming fluid and a partial 45 vacuum being caused to exist about the body. The natural tendency of the embalming fluid is to penetrate the veins and arteries and capillaries of the body. The operating chamber thus assists the operator in that the embalming fluid readily reaches all of the veins and arteries and all of the capillaries of the body thus insuring adequate 50 embalming action. In fact, it seems logical that an embalming solution of formaldehyde somewhat weaker than the customary 5% solution may be employed with more satisfactory results due to the complete saturation of the capillaries, 55 tissues and veins of the body through the above described process.

It is obvious that embalming according to the herein described method results in a better cosmetic effect in that the capillaries are themselves completely purged of blood and blood particles and refilled with suitable embalming fluid. Further, the tissues of the body which 60

may have wasted away due to illness may be adequately built up through the vacuum action in moving the embalming fluid into the same so as to refill these collapsed tissues. In summary, the method herein disclosed effectively applies respiration to the blood carrying vessels and capillaries of the body so that effective and complete embalming may take place there-through. An obvious advantage of this method over the methods heretofore known to the art is in the absence of broken capillaries, resulting in splotches which necessitate the painting or other treatment of the area in order to preserve an attractive cosmetic effect. The herein described method also permits the accurate weighing of the body fluids. For example, the amount of blood first purged from the body may be weighed and subsequent weighing of the capillary wash directed into the body as compared to the weight of the same upon its removal therefrom will result in the determining of the complete weight of the body fluids. This is important in that it enables the operator to replace these fluids accurately as to amount and proportion of the preserving fluid necessary.

What I claim is:

1. The method of embalming comprising placing a body in a chamber adapted to be sealed, connecting the deeper or larger arteries and veins of the body with conduits for drainage to the exterior of the chamber, sealing the chamber, subjecting the body to a uniform external pressure to cause blood in the vascular system to be forced out of the body and through said conduits, thereafter, when sufficiently drained and while still under pressure, connecting both arteries and veins to a liquid supply source, and then imposing a negative pressure upon the interior of the chamber and consequently the exterior of the enclosed body, to cause the liquid to be drawn into the vascular system and to be thoroughly diffused throughout the body.

2. The method of embalming wherein the draining of a body comprises placing the body in a chamber adapted to be sealed, connecting the deeper or larger arteries and veins of the body with conduits for drainage to the exterior of the chamber, sealing the chamber, subjecting the body to alternate positive and negative external pressures to cause the blood in the vascular system to be forced out of the body and through the said conduits.

3. The method of embalming comprising placing a body in a chamber adapted to be sealed, connecting the deeper or larger arteries and veins of the body with conduits for drainage to the exterior of the chamber, sealing the chamber, subjecting the body to alternate positive and negative pressures to cause the blood in the vascular system to be forced out of the body and through the said conduits, thereafter, when sufficiently drained and while still under pressure, connecting both arteries and veins to a liquid supply source and then imposing a negative pressure upon the interior of the chamber and consequently the exterior of the enclosed body, to cause the liquid to be drawn into the vascular system and to be thoroughly diffused throughout the body.

HARRY S. DAY.
